HAT

Ethel Simon, West Orange, N.J., assignor to Simon Simple Originals, Inc., Orange, N.J., a corporation of New Jersey

Filed Mar. 23, 1960, Ser. No. 59,848

Term of patent 3½ years

(Cl. D3—13)

FIG. 1

The essential features of the design are shown in full line.

I claim:

The ornamental design for a hat, as shown and described.
